CLAIM

The ornamental design for a shirt, as shown and de-
scribed.

DESCRIPTION

FIG. 1 is a perspective view of a shirt embodying the
design of the present invention;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is an enlarged fragmentary view showing the
collar portion.

The broken lines shown in FIGS. 1 through 7 are un-
derstood to represent conventional stitching.

FIG. 1
